Attorney:

UNITED STATES PATENT OFFICE.

FREDERICK A. STEVENS, OF PROVIDENCE, RHODE ISLAND.

BOOKMARK.

Application filed May 15, 1922. Serial No. 560,958.

To all whom it may concern:

Be it known that I, FREDERICK ARTHUR STEVENS, a citizen of the United States, and a resident of Providence, in the county of 5 Providence and State of Rhode Island, have invented a new and useful Improvement in Bookmarks, of which the following is a specification.

The present invention relates to book-10 marks, and its object is to provide a very simple article that shall be cheap to manufacture, but more suitable to the purpose in hand than any article of this character that has heretofore been produced.

Fig. 1 of the accompanying drawings illustrates, in reduced scale, a book-mark constructed according to a preferred embodiment of the present invention, the book-mark being shown resting on a page of an 15 open book; Fig. 2 is a fragmentary view of the line-indicating portion of the book-mark shown in Fig. 1; Fig. 3 is a similar view of the column-indicating portion of the book-mark shown in Fig. 1; Fig. 4 is a fragmentary view of a modification; Fig. 5 is a view of a combined book-mark and paper-cutter; Fig. 6 illustrates modified book-marks provided with attaching means; Figs. 7 and 8 are views of modifications; Fig. 9 is a section taken upon the line 9—9 of Fig. 8; Fig. 20 10 is a view of another modification; and Fig. 11 is a section taken upon the line 11—11 of Fig. 10.

The preferred book-mark 2 of the present 25 invention is provided with an indicating hand 4 for indicating any line of either page of a book 5. In the specific embodiment of the invention that is herein illustrated and described, the book-mark 2 is provided with a picture or other likeness 6 of an open book. The indicator 4 is pivoted at 8 approximately centrally of this likeness 6, so that the indicator 4 may be pivotally moved about the point 8, and so positioned to indicate any predetermined line of either page of the likeness. To each line of the pages of the likeness 6 corresponds a line of the pages of the book 5. As shown in Figs. 1 and 2, for example, the indicator 4 indicates a line 12 of the left-hand page 14 of the book 5.

A book-mark of this simple character can be readily and cheaply manufactured by simply cutting to size a sheet of cardboard,

celluloid, sheet-metal, and the like, printing 55 or otherwise applying the picture or likeness 6, and riveting in place, so as to render freely pivotable at 8, the indicator 4. If the riveting is properly done, the indicator will frictionally be maintained in any position in 60 which it may be set. If desired, the book-mark may be indented at a plurality of points 16, Figs. 8, 9 and 11, and the indicator may be correspondingly indented, as shown at 18, whereby the indicator may be 65 positively locked in adjusted position; but friction may be relied upon fully, as described. The desired position upon the book 5 which it is desired to indicate will thus be indicated by the book-mark irrespective 70 of the position occupied by the book-mark. The book 5 may be closed with the book-mark between the pages of the book 5; and when the book 5 is reopened, the book-mark 2 will indicate to the reader where he left 75 off reading before the book was closed. If the book-mark is made of sufficiently stiff material, it may serve also as a paper cutter, and it may then be suitably shaped, as shown in Fig. 5.

When a book is used for reference purposes, and it is desired to refer to a number of pages of the same book, it is convenient to attach a number of the book-marks, properly set, each to the corresponding 85 page. Three book-marks are shown so attached in Fig. 6, at 20, 22 and 24. On opening the book 5 to the desired page, the book-mark will there be found, indicating the proper reference line of the page. The preferred attaching means is shown as a spring clip 26. The book-mark may be provided with a number of openings 28, Figs. 6 and 7, through which the ribbon book-mark 30 90 may be passed. The book-mark of the present invention may thus be attached to the ribbon to prevent its becoming lost.

Some books are printed with a number of columns to each page. The book-mark of the present invention is therefore provided with means for indicating the desired column of the page, as well as the line of the column. The preferred construction, shown in Figs. 1 and 3, comprises a pivoted disk 32 that is provided with a plurality of column-indicating symbols, shown as numerals. As the disk is pivotally moved about its pivotal 100

point 34, the numerals will be successively exposed through an opening 36 in the book-mark. The numeral 2 is exposed in Figs. 1 and 3, which indicates the second column; and the line-indicator 4 indicates the page 14; so that the indicators 4 and 32 together indicate the desired line 12 of the second column of the left-hand page 14 of the book 5.

10 The column indicator 32 may be frictionally secured to the book-mark 2 by riveting, in the same manner as was described above in connection with the indicator 4; or it may be locked in place, as will be understood.

A column-indicating hand 38 may be employed instead of the disk 32, and it may be pivotally secured by the same rivet that secures the indicator 4 to the book-mark.

20 The indicator 4 may then be supplied with the column-indicating numerals or other symbols, as is illustrated in Figs. 4, 7, 10 and 11. The indicator 38 may be provided with an indentation 40 to cooperate with the indentations 18 for positively locking the indicator 38 in adjusted positions. Or, the column-indicating symbols may be provided upon the ribbon 30, and may be exposed through the opening 36 of the book-mark by simply sliding the book-mark back and forth along the ribbon.

Other modifications also will occur to persons skilled in the art, and all such are considered to be within the spirit and scope of the invention, as defined in the appended claims.

What is claimed as new is:

1. A device of the class described provided with a likeness of a sheet having a plurality of positions thereon, and means for indicating a predetermined position on the likeness of the sheet to correspond to a predetermined position on the sheet.

45 2. A book-mark provided with a likeness of an open book to correspond to the pages of an open book, and means for indicating a predetermined position on either page of the likeness of the open book to correspond to a predetermined position on either page of the open book.

3. A book-mark provided with a likeness of an open book to correspond to the pages of an open book, and an indicating hand pivoted approximately centrally of the likeness of the open book and adapted to be maintained in a predetermined position of pivotal adjustment to indicate a corresponding predetermined position on either page of the open book.

60 4. A book-mark as defined in claim 3 in which the indicating hand is maintained in adjusted position by friction.

5. A book-mark adapted to be inserted between the pages of a book, having, in combination, a likeness of a page to cor-

respond to the page of a book, means for indicating a predetermined position on the likeness of the page to correspond to a predetermined position on the page of the book, and means for attaching the book-mark to the page of the book.

6. A book-mark adapted to be inserted between the pages of a book and provided with an opening, and a column-indicator pivoted to the book-mark and provided with a plurality of symbols respectively corresponding to a plurality of columns of a page of a book, the indicator being concealed by the book-mark except at the opening and being adapted to be pivotally moved so as to expose a predetermined symbol through the opening.

7. A book-mark provided with an indicator each indication of which corresponds to a predetermined position on a column of a page of a book and no two indications of which correspond to the same position on the column of the page of the book, the page being provided with a plurality of columns, and an indicator each indication of which corresponds to a predetermined column of the page of the book, whereby the indications of the position indicator may be correlated with the indications of the column indicator to indicate a predetermined position of a predetermined column of a page of the book.

8. A book-mark provided with a likeness of a page to correspond to a column of the page of a book the pages of which are provided with a plurality of columns, means for indicating a predetermined position on the likeness of the page to correspond to a predetermined position on a column of the page of the book, and means for indicating a predetermined column of the page of the book, whereby the indications of the position-indicating means may be correlated with the indications of the column-indicating means to indicate a predetermined position of a predetermined column of a page of the book.

9. A book-mark provided with a plurality of adjustable indicators, one for indicating a predetermined position on a column and another for indicating a predetermined column of a page of a book, and means provided upon the book-mark and the indicators for maintaining the indicators in adjusted positions, whereby the indications of the position indicator may be correlated with the indications of the column indicator to indicate a predetermined position of a predetermined column of a page of the book.

10. A book-mark having, in combination, a likeness of a page to correspond to the page of a book, means for indicating a predetermined position on the likeness of the page to correspond to a predetermined po-

sition on the page of the book, the book-
mark having an opening, and a column in-
dicator provided with a plurality of sym-
bols respectively corresponding to a plural-
ity of the columns of the page of the book,
the column indicator being concealed by the
book-mark except at the opening and being

adapted to be positioned so as to expose a
predetermined symbol through the opening.

In testimony thereof, I have hereunto ¹⁰
subscribed my name this 11th day of May,
1922.

FREDERICK A. STEVENS.
